UNITED STATES PATENT OFFICE.

HARRY JOSEPH MATSON, OF HAVRE, FRANCE.

GEAR FOR SUPPORTING AND LAUNCHING LIFE-RAFTS.

No. 825,917.

Specification of Letters Patent.

Patented July 17, 1906.

Application filed December 22, 1905. Serial No. 292,889.

To all whom it may concern:

Be it known that I, HARRY JOSEPH MATSON, a citizen of the French Republic, and a resident of Havre, France, have invented 5 certain new and useful Improvements in Gear for Supporting and Launching Life-Rafts, (for which I have filed applications for patents in Great Britain, No. 13,900, dated July 5, 1905, and in Germany on July 10 27, 1905;) and I do hereby declare the following to be a full, clear, and exact description of the same.

This invention relates to improved gear for supporting and launching life-rafts from 15 ships' decks, the same being simple in construction and not likely to get out of order and being specially designed to permit of the instant launching of a number of life-rafts and to only require the operation of a single 20 hand-wheel or the like for the purpose.

On the accompanying drawings, Figure 1 represents a side elevation, partly in section, of the improved launching-gear arranged on a ship's deck with a raft in position. Fig. 2 25 is a rear elevation of the gear, and Fig. 3 is a plan view thereof.

The launching-gear comprises a framework consisting of side standards *a* and cross-ties *a'*, which support inclined guide-rails *b*, 30 the lower ends of which depend over the edge of the ship's deck *c*. Transversely of the framework and mounted in suitable end bearings is arranged a shaft *d*, to which are fixed two triggers *d'* and a central arm *d''*. The 35 arm is formed with a lug *d⁴*, which is adapted to engage with a catch *i⁹* on the raft to insure its launching, and is also formed with a depression *d³* in its lower edge, in which engage 40 the joint-connected ends of two struttled legs *e* and an adjustable locking-link *f*. The struttled legs are pivoted at their lower ends to a plate *g⁴*, mounted on the deck. The 45 adjustable link *f* is provided at its lower end with an eye *f'*, which is adapted to be engaged by a transversely-arranged locking-bolt *g*, which works in guides *g' g² g³*. The locking-bolt is connected at *g⁴* to an operating-rod *h*, which works in guides *h⁶ h⁷*, and is connected to a bifurcated link *h'*, which is 50 provided at its free end with a screw-threaded portion *h²*, which is engaged by an internally-screw-threaded worm-wheel mounted in a bearing *h³* and adapted to be turned by a worm *h⁴* and hand-wheel *h⁵*.

i represents a raft adapted to be launched broadwise onto the water. It is provided on

its lower side with runners *i⁷*, which engage the grooved rails *b*, and on its upper side with pulleys *i⁸* for lashing-chains. The raft when in position on the guide-rails is secured 60 against being washed away by the waves or being otherwise dislodged by lashing-chains *j*, each of which is secured to the deck at *j'* and passes through a hole *b'* in one guide-rail and is connected to a hook *d⁵* on the shaft *d*. 65

The operation of the device is as follows: When it is desired to release the raft, the hand-wheel *h⁵* is operated so as to act upon the rod *h* and bolt *g* and withdraw the latter from the eye in the adjustable locking-link *f*, 70 whereupon the struttled legs fall forward and allow the arm *d''* and shaft *d* to rotate and also the triggers *d'* and the lug *d⁴* to strike against the catch *i⁹* on the raft and the hooks *d⁵* to disengage themselves from the ends of 75 the chains, so as to release the raft and cause it to run down the inclined rails into the sea. A plurality of the launching-gears each with a raft thereon may be arranged at the edge of the ship's deck, in which case the operating-rod *h* can be connected to each one of the series of gears, so as to launch all the rafts simultaneously.

What I claim as my invention, and desire to secure by Letters Patent, is— 85

1. In gear for supporting and launching a life-raft, in combination, inclined guide-rails, means for supporting said rails, a rotatable shaft mounted in suitable bearings transversely of and below said rails, triggers fast 90 on said shaft for supporting the raft, and releasable means for controlling the rotation of said shaft, as set forth.

2. In gear for supporting and launching a life-raft, in combination, inclined guide-rails, 95 means for supporting said rails, a rotatable shaft mounted in suitable bearings transversely of and below said rails, triggers fast on said shaft for supporting the shaft, an arm also fast on said shaft for controlling its rotation, and means for releasably supporting said arm, as set forth.

3. In gear for supporting and launching a life-raft, in combination, inclined guide-rails, means for supporting said rails, a rotatable 105 shaft mounted in suitable bearings transversely of and below said rails, triggers fast on said shaft for supporting the raft, an arm also fast on said shaft for controlling its rotation, struttled legs pivotally mounted at their 110 lower ends, an adjustable locking-link joint-connected at its upper end to the upper ends

of said legs, said legs and link serving to support said arm, and a withdrawable bolt serving to secure the locking-link at its lower end, as set forth.

- 5 4. In gear for supporting and launching a life-raft, in combination, inclined guide-rails, means for supporting said rails, a rotatable shaft mounted in suitable bearings transversely of and below said rails, triggers fast 10 on said shaft for supporting the raft, an arm also fast on said shaft for controlling its rotation, strutted legs pivotally mounted at their lower ends, an adjustable locking-link joint-connected at its upper end to the upper ends 15 of said legs, said legs and link serving to support said arm, a withdrawable bolt serving to secure the locking-link at its lower end, a guided rod connected to said locking-bolt, and a bifurcated link connected at one end to 20 said rod and provided at the other end with a screw-threaded part which is operable by a hand-wheel, as set forth.
- 5 5. In gear for supporting and launching a life-raft, in combination, inclined guide-rails, 25 means for supporting said rails, a rotatable shaft mounted in suitable bearings transversely of and below said rails, triggers fast on said shaft for supporting the raft, a lug fast on said shaft for impelling the raft, and 30 releasable means for controlling the rotation of said shaft, as set forth.

6. In gear for supporting and launching a life-raft, in combination, inclined guide-rails, means for supporting said rails, a rotatable shaft mounted in suitable bearings transversely of and below said rails, triggers fast 35

on said shaft for supporting the raft, hooks fast on said shaft, adjustable raft-lashing chains each made fast at one end to a suitable base and engageable at its other end by 40 one of said hooks, and releasable means for controlling the rotation of said shaft, as set forth.

7. In gear for supporting and launching a life-raft, in combination, inclined guide-rails, 45 means for supporting said rails, a rotatable shaft mounted in suitable bearings transversely of and below said rails, triggers fast on said shaft for supporting the raft, a lug fast 50 on said shaft for impelling the raft, hooks fast on said shaft, adjustable raft-lashing chains each made fast at one end to a suitable base and engageable at its other end by one of 55 said hooks, and releasable means for controlling the rotation of said shaft, as set forth.

8. In gear for supporting and launching a plurality of life-rafts simultaneously, in combination, a plurality of guide-rails suitably supported, a rotatable shaft mounted in suitable bearings transversely of and below each 60 pair of said rails, triggers fast on each said shaft for supporting said rafts, and means for controlling the rotation of each said shaft, said latter means being connected together and simultaneously operable by a common 65 operating-rod, as set forth.

In witness whereof I have hereunto set my hand in the presence of two witnesses.

HARRY JOSEPH MATSON.
